DESIGN FOR A VENTILATED FINGER RING

William R. Rowan, North Attleboro, Mass.

Application August 26, 1941, Serial No. 103,016

Term of patent 3½ years

To all whom it may concern:

Be it known that I, William R. Rowan, a citizen of the United States of America, residing at North Attleboro, county of Bristol, State of Massachusetts, have invented a new, original, and ornamental Design for a Ventilated Finger Ring, of which the following is a specification, reference being had to the accompanying drawing forming a part thereof.

Fig. 1 is a top plan view of a ventilated finger ring showing my new design;

Fig. 2 is an edge view; and

Fig. 3 is a section on line 3—3 of Fig. 2 thereof. The dominant feature of my design resides in the portions shown in full lines.

I claim:

The ornamental design for a ventilated finger ring, substantially as shown and described.

WILLIAM R. ROWAN.
